VERTICAL VENETIAN BLIND

Maurice E. Achler and Albert H. Milstine, Chicago, Ill., assignors of one-tenth to Harry Shapiro, Chicago, Ill.

Application March 27, 1952, Serial No. 278,857

7 Claims. (Cl. 160—172)

This invention relates to Venetian blinds, and is concerned more particularly with vertical Venetian blinds.

An object of our invention is to provide a vertical Venetian blind whose slats are readily removable and replaceable and easy to clean.

Another object is to provide a vertical Venetian blind having a group of slats adapted to be progressively collapsed and extended.

A further object is to provide a vertical Venetian blind whose parts are adapted to be readily assembled and disassembled.

It is also an object to provide a Venetian blind in which preselected groups of slats may be separated to any desired extent.

An additional object is to provide a vertical Venetian blind in which bulging of the slats is precluded.

It is a further object to provide an improved mounting for the slats of a vertical Venetian blind.

Another object is to provide improved slat suspending structure.

It is also an object to provide a vertical Venetian blind which may be manufactured at low cost and quickly installed in a window.

Further objects and advantages of the invention will appear as the description proceeds.

The invention will be better understood upon reference to the following description and accompanying drawings, in which:

Fig. 1 is a front elevational view of an embodiment of the invention comprising two groups of slats installed in a window frame, the slats being adjusted in non-overlapped uniformly spaced relation, and the facia boards being omitted.

Fig. 2 is similar to Fig. 1 but shows the slats adjusted into two separated groups.

Fig. 3 is an enlargement of a portion of the upper structure appearing in Fig. 1.

Fig. 4 is a sectional view taken as indicated by the line 4—4 in Fig. 3.

Fig. 5 is a view, partly in section and partly in elevation, taken as indicated by the line 5—5 in Fig. 4 and showing details of the left corner construction of the blind, including the mechanism for adjusting the degree of tilt of the slats, the slats being here shown as in Fig. 2.

Figs. 6, 7, and 8 are sectional views taken as indicated by the lines 6—6, 7—7, and 8—8, respectively in Fig. 5.

Fig. 9 is a front view, partly in elevation and partly in section, showing a few of the slats in fully lapped relation.

Fig. 10 is a sectional view taken as indicated by the line 10—10 in Fig. 9, showing also in dot-dash lines the disposition of the slats when the control tube is fully turned in the reverse direction.

Fig. 11 is a detail of a section of the bottom chain appearing in Fig. 9.

Fig. 12 is an isometric view of one of the sliders.

Fig. 13 is taken in the same plane as Fig. 5 but shows

the connections with the traverse cord and also the centering structure for a double section blind.

Fig. 14 is an enlarged sectional view taken as indicated by the line 14—14 in Fig. 13.

Fig. 15 is taken in the same plane as Fig. 5 but shows the right upper installation bracket and associated structure.

Figs. 16 and 17 are respectively sectional and plan views taken as indicated by the lines 16—16 and 17—17 in Fig. 15.

Fig. 18 is similar to Fig. 13 but shows a modification.

Figs. 19 and 20 are sectional views taken as indicated by the lines 19—19 and 20—20, respectively, in Fig. 18.

Fig. 21 is similar to the bottom of Fig. 9 but shows a modification.

Fig. 22 is a sectional view taken as indicated by the line 22—22 in Fig. 21.

Referring now more particularly to the drawings, disclosing illustrative embodiments of the invention, there is shown a window casing 28 in which is installed a vertical Venetian blind constructed in accordance with one form of the invention. The blind comprises a left installation bracket 30 having a web 32 secured as by screws 34 to the upper left side 36 of the casing 28 and having a rear flange 38 with a lower upstanding lip 40 for the receasable reception of a rear facia board 42. A supplemental bracket 44 is riveted as at 46 or otherwise suitably connected to the installation bracket 30 and may have a lower outwardly extending flange 48 which may abut the bracket 20 web 32, and has an upstanding portion 50 journaling a horizontal stud 54 on which a gear sector 56 is mounted, whereby the gear sector is tiltable about the axis of the stud. The gear sector 56 has a substantially ring-like extension 60 embracing the left end portion 62 of a horizontal rod 66 which is preferably in the form of a tube having throughout the length thereof a slot 68 in which a tongue 70 on said extension projects, so that the tube will rotate with the gear sector.

The yoke 76 is clinched as at 78 or otherwise suitably attached to the portion 50 of the supplemental bracket 44, a horizontal shaft 80 is journaled between the portion 50 and the arms 82 of the yoke, and a worm 84 integral with or fixed to the shaft is in mesh with the gear sector 56, the portion 50 being cut away as at 85 to provide clearance for the worm. The shaft 80 has an outer end 86 to which is keyed or otherwise affixed a sheave 88 over which runs a tilt-cord 90, and a tilt-cord guide 92 is mounted about said shaft end and has projections, one of which is shown at 94, for engagement with the portion 50 and yoke, respectively, to limit tilt of the guide pursuant to pull of the cord. It will now be apparent that when the tassel 100 attached to one end portion 102 of the cord 90 is pulled, the tube 66 will be turned in one direction, and when the tassel 104 is attached to the other end portion 106 of the cord is pulled, the tube will be turned in the opposite direction.

A bracket element 108 pivoted at 110 to the lower front portion of the installation bracket 30 is formed to receive and retain the front facia board 112. The facia boards 40 42 and 112 are for the most part omitted from other figures of the drawings in order that more essential parts of the invention may be shown.

A right upper installation bracket 114 fits the upper right corner of the casing 28 and includes a web 116 screwed or otherwise attached to the right side 118 of the casing. A yoke 120 has wings 122 at the free ends of its arms 124, and rivets 126 or the like fasten said wings to the web 116. Two sheaves 127 and 128 separated by a spacer 130 are disposed about an axle 132 journaled in the yoke arms 124, the axle being inclined upward toward the front (i. e., the inner part of the

room), for a purpose which will appear. The bight 134 of the bracket 120 is formed with a substantially half-round saddle 136 serving as the bearing for the right end portion 138 of the tube 66, said bearing being coaxial with the gear sector 56. Clearance is afforded at 140 between the top 142 of the casing 28 and the upper parts 144 of the arms 124 to enable the right end 138 of the tube 66, after it has been moved to the right out of the extension 60, to be lifted out of the bearing 136 and then moved forward in the space 140 and then pulled free. Provision may be made to prevent accidental escape of the tube 66. It is obvious that by reverse movements the tube 66 may be installed in the position shown.

The slats 150 may be formed of sheet aluminum, steel, or other metal, or of wood, plastic or other suitable material, but are preferably formed of sheet steel transversely bowed substantially as shown, with centered holes 152 at the upper ends 154 thereof for the releasable reception of hooks 156 formed to cause the slats to rotate therewith. Each hook 156 has an extension 158 formed with a slot 160 through which a piece of tape 162 is looped, the two ends 164 of the tape being disposed between a washer 166 and a strip of tape 168 over which is disposed the bight 170 of a generally U-shaped slider 172, and in this arrangement fastened together as by a hollow rivet 174. The arms 176 of each slider 172 have wings 178 flaring away from each other, and the proximate portions 180 of the arms are adapted to be extended into the tube slot 68 and slidably engage the tube 66 adjacent the sides 182 of the slot. The several slats 150 are adapted in this way to be assembled with the tube 66.

The sliders 172 are arranged in two strings 186 in the illustrated embodiment of the invention, each string including a tape 168 by which the several sliders are connected in succession.

When the tube 66 is arranged with its slot 66 lowermost, the intermediate portions 190 of the folded tapes 162, and consequently the slats 150, extend in planes substantially parallel to the sides of the casing 28. When the tube 66 is turned from that position, each tape 162 follows the path of least resistance pursuant to the gravity pull of the associated slat, with the result that the tape turns gradually in front of the rivet 174, thereby turning the associated slat. Thus when the tube 66 is turned to the fullest extent, the intermediate portion 190 of each tape extends in a plane substantially parallel to the axis of the tube, and consequently the slat 150 associated therewith extends in substantially the same plane, so that the several slats are in such overlapped relation as to block the passage of light. The tube 66 will remain in any position to which it is adjusted by the tilt cord 102, and the position of the tube determines the angles which the slats make with the window.

A sheave 194 is journaled in the arms 196 of a yoke 198 having opposite struck-out tongues 200 engaging the left extremity 202 of the tube 66, the arms having spring ends 204 which resiliently and frictionally engage opposite portions of the inner surface 206 of the tube and thus detachably retain the sheave in the tube. A traverse pull cord 210 is looped about the sheave 194, the portions 212 and 214 of said cord, extending to the right from said sheave, passing along and within the tube 66 and out of the end 138 of the tube and being engaged with the respective sheaves 127 and 128, from which they depend and terminate in tassels 216 and 218, respectively. The cord portion 212 between the sheave 194 and the end 138 of the tube 66 in one form of the invention extends through a spring loop 220 disposed over the hollow rivet 174 associated with the innermost slider 172 of one string 186, and a screw 221 threaded to a sleeve extension 222 of the loop presses against the loop and binds the cord portion 212 therein so that said innermost slider will move with said cord portion. The other cord portion 214 is similarly connected with the innermost end slider

172 of the other string 186. It is therefore apparent that when one cord portion 212 is pulled, both strings 186, and accordingly the group of slats 150 associated therewith, will be collapsed, and when the other cord portion 214 is pulled, the strings and slats will be reextended.

A chain 224, such as a pull chain, extends horizontally below the lower ends of the slats 150 of each group, the outer end 226 of each chain being connected as by a spring 228 to the adjacent side wall of the casing 28, and 10 the inner ends of the chains being provided with respectively an eye 230 and a hook 232 so that the chains may be detachably coupled. When the chains 224 are coupled, they extend in substantially a straight line, as shown. In one form of the invention, hooks 234 connect and are 15 swiveled to chain sections 235 and are adapted to be passed through holes 236 arranged centrally at the lower ends 238 of the slats 150, and when the hooks are disposed in said holes, the bottoms of the slats are held in substantially a straight line directly below and parallel 20 to the tube 66. The arms 240 of the hooks 234 are preferably relatively flat so as to turn with the slats 150. The upper hooks 156 are similarly formed so that the slats 150 and upper hooks will turn together. To assemble the slats 150 with the several hooks 156 and 234, the slats are 25 placed with their upper holes 152 at the tips of the upper hooks and angled very slightly and then lowered into the upper hooks to be suspended thereby, and the lower hooks 234 may then be raised and slipped through the holes in the lower ends of the slats; and by reverse action, the slats may be removed. It will be obvious from the description and the drawings that the task of applying and removing the slats is an exceedingly simple one.

The sheaves 127 and 128 are arranged with their axis inclined upward toward the room due to the fact that 35 when either tassel 216 or 218 is pulled, it is generally moved toward the person pulling it as well as downward, so that the direction of pull is in a line inclined somewhat forward and downward. Thus the direction of pull is in 40 the plane of the groove of the sheave involved, so that resistance is minimized.

The slats 150 may be of any suitable width, but are 45 preferably two inches wide, and the sliders 172, when the strings are fully extended, are then arranged $1\frac{3}{4}$ " on centers, so that the slats, when fully overlapped, lap one another $\frac{1}{8}$ ".

A stiff center piece 250 is disposed between the innermost sliders 172, as shown in Fig. 13, and is supported by the tube 66 by means of a slider 252 extending through the tube slot 68 and riveted as at 254 or otherwise suitably connected to the center piece. When the center piece 250 is engaged by the innermost end sliders 172, the slider strings are fully extended. The length of the center piece 250 is such that, when engaged by 55 the innermost end sliders 172, said sliders are spaced $1\frac{3}{4}$ " on centers so as to preserve the uniformity of the spacing throughout the entire blind.

A modified center construction and traverse cord anchoring means is shown in Fig. 18. In this form of the 60 invention, the innermost end sliders 172 are like the remaining sliders of the strings, and are riveted as at 258 to tongues 260 formed on stiff center plates 262 adapted to mutually abut at 264 when the strings are fully extended. When the plates 262 so abut, the adjacent sliders 65 172 are spaced apart $1\frac{3}{4}$ " on centers to preserve uniformity of spacing throughout the entire width of the blind when fully extended. Each plate 262 has a depressed relatively narrow tongue, and the cord portions 212 and 214 are looped about these tongues and are 70 tightly held thereby so that the plates and cord portions move in unison.

A modified lower hook construction is shown in Figs. 21 and 22, and comprises hooks 270 riveted as at 272 to the lower ends of the slats 150, the hooks engaging 75 in upper eyes 274 of short pull chain members 276 hav-

ing lower eyes 278 looped about suitably spaced links of bottom chains 280 corresponding to the chains 224.

Various modifications may suggest themselves to those skilled in the art without departing from the spirit of our invention. Hence we do not wish to be restricted to the specific forms shown or uses mentioned, except to the extent indicated in the appended claims, which are to be interpreted as broadly as the state of the art will permit.

We claim:

1. In a vertical Venetian blind, a horizontal tube having a straight slot throughout its length and supported for rocking about a horizontal axis, a series of sliders supported by said tube and each having a portion extending through said slot, the outermost surface of each of said portions being substantially flat, a flexible foldable tape having a first portion secured contiguously to each of said slider surfaces, the securing means including a single fastening element passing through said first tape portion substantially medially of the width thereof, said element having a substantially circular head portion, said tape having a second portion depending in angular relation from said first tape portion substantially at an edge of said circular head portion, the line of juncture between said first and second portions being caused to progressively shift along the edge of said circular head portion as said tube is rocked in one direction or another, and a slat suspended from each of said second tape portions.

2. In a vertical Venetian blind, a horizontal tube having a straight slot throughout its length and supported for rocking about a horizontal axis, a series of sliders supported by said tube and each having a portion extending through said slot, the outermost surface of each of said portions being substantially flat, flexible foldable means connecting said slides in successive relation, a flexible foldable tape having a first portion secured contiguously to each of said slider surfaces, the securing means including a single fastening element passing through said first tape portion substantially medially of the width thereof, said element having a substantially circular head portion, said tape having a second portion depending in angular relation from said first tape portion substantially at an edge of said circular head portion, the line of juncture between said first and second portions being caused to progressively shift along the edge of said circular head portion as said tube is rocked in one direction or another, and a slat suspended from each of said second tape portions.

3. In a vertical Venetian blind, a horizontal tube having a straight slot throughout its length and supported for rocking about a horizontal axis, a series of sliders supported by said tube and each having a portion extending through said slot, the outermost surface of each of said portions being substantially flat, flexible foldable tapes each having first and second portions, a single fastening element securing the first portion of said tapes contiguously to respective slider surfaces, said fastening element having a tape engaging portion having a convexly curved edge extending transversely across said tape portion, the second portion of each of said tapes depending in angular relation from the first portion substantially at said convexly curved edge, the line of juncture between said first and second tape portions being caused to progressively shift along said convexly curved edge as said tube is rocked in one direction or another, and a slat depending from each of said second tape portions.

4. In a vertical Venetian blind, a horizontal tube having a straight slot throughout its length and supported for rocking about a horizontal axis, a series of sliders supported by said tube and each having a portion extending through said slot, the outermost surface of each of said portions being substantially flat, flexible foldable tapes each having first and second portions, flexible foldable means connecting said slides in successive relation, a single fastening element securing the first portions of said tapes and said flexible foldable means to respective

slider surfaces, said fastening element having a tape engaging portion having a convexly curved edge extending transversely across said tape portion, the second portion of each of said tapes depending in angular relation from the first portion substantially at said convexly curved edge, the line of juncture between said first and second tape portions being caused to progressively shift along said convexly curved edge as said tube is rocked in one direction or another, and a slat depending from each of said second tape portions.

5. In a vertical Venetian blind, a horizontal member supported for rocking about a horizontal axis, a series of sliders supported by said member and each having an outer surface which is substantially flat, a flexible foldable tape having a first portion secured contiguously to each of said slider surfaces, the securing means including a single fastening element passing through said first tape portion substantially medially of the width thereof, said element having a substantially circular head portion, said tape having a second portion depending in angular relation from said first tape portion substantially at an edge of said circular head portion, the line of juncture between said first and second portions being caused to progressively shift along the edge of said circular head portion as said member is rocked in one direction or another, and a slat suspended from each of said second tape portions.

6. In a vertical Venetian blind, a horizontal member supported for rocking about a horizontal axis, a series of sliders supported by said member and each having an outer surface which is substantially flat, flexible foldable means connecting said slides in successive relation, a flexible foldable tape having a first portion secured contiguously to each of said slider surfaces, the securing means including a single fastening element passing through said first tape portion substantially medially of the width thereof, said element having a substantially circular head portion, said tape having a second portion depending in angular relation from said first tape portion substantially at an edge of said circular head portion, the line of juncture between said first and second portions being caused to progressively shift along the edge of said circular head portion as said member is rocked in one direction or another, and a slat suspended from each of said second tape portions.

7. In a vertical Venetian blind, a horizontal tube mounted to rotate about a horizontal axis and having a horizontal slot therethrough, a string of sliders supported by and rotatable with said tube and extending in said slot, flexible foldable means connecting said slides in successive relation, a slat for each slider, means suspending each slat from a slider, said means comprising a flexible foldable tape having a first portion secured contiguously to an outer surface of each slider, the securing means including a single fastening element passing through said first tape portion substantially medially of the width thereof, said fastening element having a substantially circular head portion, said tape having a second portion depending in angular relation from said first tape portion substantially at an edge of said circular head portion, said means being constructed and arranged to automatically turn said slats about substantially vertical axes pursuant to rotation of said tube, the line of juncture between said first and second tape portions being caused to progressively shift along the edge of said circular head portion as said tube is rocked in one direction or another, a sheave adjacent an end of and rotatable with said tube, a traverse cord looped about said sheave, both portions of said cord extending directly from said sheave within and along said tube, one portion of said cord within said tube being connected to an end slider of said string whereby said cord is operative to selectively collapse and extend said string, and means for turning said tube about said axis.
